DRY MATERIAL AGITATING AND MEASURING APPARATUS

Elmer E. Harper, Kansas City, Mo.

Application April 22, 1933, Serial No. 667,417

4 Claims. (Cl. 259—31)

The present invention relates to apparatus designed for the handling of dry materials in granular form or in a more or less fine, coarse or lumpy condition, and has particular reference to installations using chemical materials where means must be provided for feeding and measuring such materials in the course of their use.

It is therefore one of the purposes of the invention to provide a practical and efficient arrangement for accommodating a supply of material in a tank, bin or other container, from which the material may be discharged in measured quantities as required, together with means for effecting a continuous discharge of the material from such container throughout the period of operation until substantially all the contents are delivered to the discharge point or until the supply of material is renewed. At the same time it is one of the objects of my construction to produce a sufficient agitation of the contents of the tank to promote the feeding and discharging of the material at the point or points provided for that purpose.

Accordingly, as one form of the improved construction, I have devised an apparatus in which means is employed to operate in a manner for continuously agitating and removing the upper surface layer of the material, which operation is carried out in a progressive downward direction, as the level of the material is lowered toward the bottom of the tank. In the construction illustrated herein, the agitating action of the feeding means is accompanied by a feeding action whereby the material is continuously conveyed to one side of the apparatus in position for delivery to a feeding and measuring device, with which the present improvements are designed to be used to constitute a complete unit or assembly for the feeding and measuring of such dry materials.

With these general objects in view, the invention will now be more particularly described by reference to the accompanying drawing showing details of such an equipment, after which the several combinations and features thereof deemed to be novel will be set forth and claimed.

In the drawing:

Figure 1 is a sectional elevation showing a feeding and measuring apparatus constructed in accordance with the present invention;

Figure 2 is a plan view of the same;

Figure 3 is a horizontal sectional view, representing a section taken on the line 3—3 of Figure 1; and

Figure 4 is an enlarged detailed section, repre-

senting a section taken on the line 4—4 of Figure 3.

In installations of the character in question, which require the handling of dry materials, such as chemical materials for use in water treating and purifying systems, bins and hoppers are commonly provided for storing the material in quantities to cover the needs of operations for a given period of time, such as 24 hours, more or less. Since the usual arrangement includes a device for controlling the rate of feed or discharge of the material into a mixing chamber or the like (ordinarily termed feeding and measuring devices), the hopper is generally of such dimensions and proportions (most usually of conical form) as to provide for the flow of the material by gravity to this feeding and measuring device, which must accordingly be at a somewhat lower level. Such a construction necessitates hoppers or bins of considerable height and relatively small diameter, and the use of agitating means is required inside the hopper to keep the material moving through the same continuously down to the outlet into the feeding and measuring device.

With an assembly of such a height it is customary to provide a platform from which to fill the bin or hopper from time to time, or else, as usually is the case, provide for supplying the material thereto from an upper storage room or floor. From this it may be seen that installations of this type not only require ample space facilities for their accommodation but also entail relatively high structural costs, which it is one of the objects of the present invention materially to reduce, or to eliminate as much as possible.

Referring to the drawing, I illustrate the container for the material as a plain, substantially cylindrical tank 10, the bottom and side wall of which are shown as formed with an opening 11 designed as an outlet to the feeding and measuring device, which may be of any desired type and in the present instance is shown as of the rotary grooved disk type, following the construction outlined in my co-pending application Serial #649,808, filed January 2, 1933. Briefly the same comprises a receptacle 12 provided with a vertical shaft 14 carrying a disk 15 formed with a channel or groove 16 into which projects a blade 17 adjustably mounted outside the receptacle for displacing all or part of the material from the groove, as determined by the blade's adjustment, and thus delivering measured quantities of the material into the mixing chamber (not shown), all as explained in greater detail in said co-pending application.

Within the tank 10 is arranged a shaft 20, illustrated as of square cross-section and mounted in a bottom step bearing 21 and an upper bearing member 22 carried by the upper deck 23 of the tank. Mounted for rotary movement with this shaft, as well as for vertical sliding movement thereon, is a material agitating and feeding member in the form of what may be termed a floating scraper device comprising a disk 24 having a 5 square opening for the shaft 20 and carrying a pair of oppositely projecting and slightly inclined blades 25 designed to ride or float upon the top 10 of the mass of material in the tank.

The blades 25 are transversely tilted, so that 15 their forward edges, with reference to the direction of travel (represented by the arrow in Figure 3) are positioned slightly higher than their rear edges, and to the rear of each blade may be connected, by means of a drag link 28 for trailing purposes, a scoop or scraper member 30, one end of 20 which is attached to the corresponding blade, as indicated at 31.

While the full weight of the scraper device just 25 described may be left supported by the mass of material in the tank, means is provided for counter-balancing more or less of this weight and thereby varying to a corresponding degree the agitating and scraping function of the device. This means is represented as a windlass comprising a shaft 30 33 supported by brackets 34 on the upper deck 23 and carrying a series of drum elements 35 for operating a series of chains, including a chain 36 carrying a set of weights 37, and a pair of chains 38 let down within the tank for supporting a lifting bar 39 provided with an opening 40 rotatably engaging the hub of the disk 24, to which is attached a keeper plate 42 for retaining engagement with said bar 39. The chain 36 carrying the weights is wound oppositely from the chains 40 38, so that it is evident that said weights serve to counterbalance part of the weight of the scraper device without interfering in any way with the operation of the latter. The outer end of the shaft 33 carries a handle 43 whereby the upper device 45 may be elevated and retained in this position by pawl and ratchet means 34 when necessary to refill the tank, for which purpose one side of the upper deck is provided with a hinged section 23' as shown in Figure 2.

50 Any appropriate driving mechanism and arrangement may be adopted for imparting the necessary rotary movement to the shafts 14 and 20, the arrangement herein shown comprising a motor 48 mounted on the deck 23 and connected by 55 a belt 49 to a speed changer 50, the crank disk 51 of which is adjustably connected by a link 52 to the arm 53 of a clutch drive device 54 attached to the upper end of the shaft 14. By these drive connections an intermittent movement is imparted to said shaft 14, which movement is also transmitted to the shaft 20 by a sprocket chain operating around wheels 56 and 57 at the upper ends of the shafts 14 and 20 respectively.

In the use of the apparatus, the tank is supplied 65 with a quantity of the material after first elevating the floating scraper device by means of the windlass, and holding it in this raised position by means of the ratchet device 44, the hinged top section 23' being opened to permit the material 70 to be dumped in beneath the scraper, whereupon the ratchet is released and the scraper lowered onto the surface of the material, and the hinged member 23' closed. The weights 37 are adjusted to obtain the desired pressure of the scraper member 75 upon the surface of the material, according

to its fineness or coarseness, and the effectiveness with which it is proposed that the device shall take hold of the material, since this of course will vary in a measure according to the weight with which it is allowed to rest upon the material and the digging, scraping and conveying function will vary to a corresponding degree. Different types or sizes and weights of scraping devices may be employed, with plow or digger elements to correspond, according to the different character of the material to be handled, since by such adaptation of the equipment it is evident that the same may be made to operate with practically any grade of dry material, varying in its nature from a fine powder to lumps up to an inch or more in diameter. 10 Thus, as the material is stirred, agitated and loosened by the action of the floating scraping member, it is swept forward in the direction of the arrow (Figure 3) around the tank to the opening 11, and there discharged into the chamber 12 to 15 the feeding and measuring device.

It will therefore be seen that a practical and efficient arrangement and construction are provided for the purposes of the invention, and that the improved apparatus is adapted to eliminate 20 the necessity of some of the expensive features of similar equipment, such as the relatively high structures with their small diameters and need of platforms or upper storage rooms for loading the hoppers. Such accessories are not required 25 with the improved construction, and it is apparent that it also makes possible the use of a tank of any desired diameter, according to the capacity needed. Moreover the operation is more convenient as well as cleaner, due to the relatively 30 shallow character of the tank, since no lifting and dumping of materials to any appreciable extent is required which always creates clouds of dust in the case of fine and powdered materials.

Many minor changes are of course possible and 35 desirable for adapting the improved construction to meet varying conditions of operation, and while I have illustrated and described one suitable and practical form of equipment for the 40 practice of my invention I desire to be understood as reserving the right to make whatever 45 changes and modifications may fairly fall within the spirit and scope of the appended claims.

Having described my invention, what I claim 50 is:

1. Apparatus of the character described comprising a receptacle for material and having an outlet for the discharge of the material from the receptacle, a floating scraper device mounted 55 within the receptacle for scraping movement upon the surface of the material therein, means for counterbalancing only a part of the weight of said device during its operative movement while permitting lowering of the device during 60 settling of said material, and means for actuating said device to agitate the material and impart movement thereto in the direction of said discharge outlet.

2. Apparatus of the character described comprising a receptacle for material and having an outlet for the discharge of the material from the receptacle, a floating scraper device mounted both for scraping movement upon the surface and also for settling movement with the material within the receptacle, said device comprising one or more blades transversely tilted with reference to the top surface of the material, and means for actuating said device to agitate the material and impart material-feeding movement 70 75 75

thereto in the direction of said discharge outlet.

3. Apparatus of the character described comprising a receptacle for material and having an outlet for the discharge of the material from the receptacle, a floating scraper device mounted within the receptacle both for scraping movement upon the surface and also for settling movement with the material therein, said device comprising one or more blades transversely tilted with reference to the top surface of the material and a scraper blade trailed in angular relation to each of said first blades, and means for actuating said device to agitate the material and impart feeding movement thereto in the direction of said discharge outlet.

4. Apparatus of the character described com-

prising a receptacle for material and having an outlet for the discharge of the material from the receptacle, a floating scraper and material-feeding device mounted within the receptacle both for scraping movement upon the surface and also for settling movement with the material therein, said device comprising one or more curved blades transversely tilted with reference to the top surface of the material and presenting their convex faces in the direction of travel of said blades, and means for actuating said device to agitate the material and impart feeding movement thereto in the direction of said discharge outlet.
